ATTORNEY

UNITED STATES PATENT OFFICE.

JUDSON C. EUBANK, OF CHICAGO, ILLINOIS.

SHIRT CUFF.

Application filed September 25, 1922. Serial No. 590,263.

To all whom it may concern:

Be it known that I, JUDSON C. EUBANK, a citizen of the United States, residing at Chicago, in the county of Cook and State of Illinois, have invented a certain new and useful 5 Shirt Cuff, of which the following is a specification.

My invention relates to improvements in men's outer shirts and, more particularly, to 10 shirt cuffs of the "soft" or "French" type.

The object of my invention is to furnish an endless detachable cuff of soft material which can, when one or more edges are soiled, be conveniently reversed, folded, adjusted or 15 turned so as to expose a fresh, clean edge for use.

Features of the invention, other than those adverted to, will be apparent from the hereinafter detailed description and claims, when 20 read in conjunction with the accompanying drawings.

The accompanying drawings illustrate one practical embodiment of the invention, but the construction therein shown is to be understood 25 as illustrative, only, and not as describing the limits of the invention.

Figure 1 is a plan view of the blank from which my endless cuff is made.

Figure 2 is a perspective view showing the 30 cuff in use, attached to the wristband of the shirt sleeve; and

Figure 3 shows the cuff attached to the wristband and the parts laid open.

Referring to Figure 1, which shows the 35 blank from which the cuff is made, it will be seen that the blank is rectangular and its ends 9 and 9^a are sewed, woven or otherwise put together so as to make the blank a continuous or endless piece of material.

40 The blank is preferably made of two or more plies of material put together by rows of stitching 10 and 11, along the edges of each side of the blank.

Button holes 1, 2, 3, 4, 5, 6, 7 and 8 are then 45 cut and sewed into the blank near the open sides thereof. These button holes are spaced an equal distance apart and the button holes on one side of the cuff blank are placed exactly opposite the button holes on the other 50 side of the blank, so that when the cuff is folded in use the button holes on one side will register with those on the other side and may be fastened together with a button or cuff link.

55 The ends 9 and 9^a of the cuff blank are

then sewed, woven or otherwise put together, making an endless, detachable cuff.

After the cuff blank has been made endless, it can readily be seen that if the cuff is folded along the dotted lines A and C button holes 60 1 and 3 will register with each other, as also will button holes 2 and 4, 5 and 7, 6 and 8.

Folded along the dotted lines B and D the button holes 3 and 5 will register with each other, as will button holes 4 and 6, 1 and 7, 65 2 and 8.

The cuff, being open at both sides, may be turned inside out and, when folded along the same dotted lines, will cause the same button holes to register with each other in 70 the same manner.

In Figure 2 the cuff is shown attached to the wristband for use and folded along the lines A and C, the fold along the line A presenting a surface or portion of the 75 cuff for use. When the cuff becomes soiled or worn along the line A, the cuff is removed from the wristband of the shirt sleeve and the position of the folded portion along line A is shifted to the place of line C near 80 the wristband and the folded portion along line C is presented for use in the place of A.

When both A and C have become soiled or worn the cuff is then folded along the 85 lines B and D and the positions of B and D are transposed as in the case of A and C.

When the cuff is folded along the lines A and C it is readily apparent that the wearer of the cuff has the advantage of two clean 90 portions of the cuff which may be easily and conveniently transposed upon the wristband of the shirt sleeve. Two more clean portions of the cuff are similarly brought into use by folding the cuff along the lines 95 B and D. Thus it will be seen that the outside surface of my endless cuff has four separate and distinct portions which may be quickly and conveniently brought into use, one after another as portions thereof become soiled or worn.

When the four portions of the outside surface of the cuff become soiled or worn the cuff may then be turned inside out and four additional clean portions are presented 105 for use in the manner heretofore described.

In Figure 3 the cuff is folded along the lines A and C, causing button holes 1 and 3 to register with each other and also button holes 2 and 4. This folding of the cuff 110

also causes button holes 5 and 7 to register with each other and also button holes 6 and 8. Button holes 5 and 7 are placed into registry with button hole 12 in the 5 wristband of the shirt sleeve, and button holes 6 and 8 are placed into registry with button hole 13 in the wristband, and the cuff is attached to the wristband of the shirt sleeve by means of a button or cuff 10 link inserted through button holes 5, 7, 6 and 8 in the cuff and 12 and 13 in the wristband. The cuff is fastened together around the wrist by means of a button or cufflink inserted through button holes 1, 3, 2 and 15 4 in the cuff. When the portion A is transposed to portions C the buttonholes 1, 3, 2 and 4 take the place of buttonholes 5, 7, 6 and 8 and vice versa. When the cuff is folded along the lines B and D the cuff is 20 attached to the wristband by using buttonholes 1, 7, 2 and 8 and the cuff is fastened together around the wrist by using buttonholes 3, 5 and 4 and 6. When the portion B is transposed to portion D, the buttonholes, 25 1, 7, 2 and 8 take the place of buttonholes 3, 5, 4 and 6 and vice versa.

When the cuff is turned inside out, it is apparent that the buttonholes are used in the same positions and in exactly the same 30 manner as above described.

My endless, detachable cuff is simple in design and construction and affords the wearer eight separate and distinct portions of the cuff which may be easily and 35 conveniently brought into use one after another as needed.

When the wearer of my cuff has his coat off the cuff presents a neat, dressy appearance and when a coat is worn, the cuff is 40 identically the same in appearance as any ordinary folded soft cuff, regardless of which one of the eight cuff portions protrudes from the coat sleeve. My cuff is easily attached to, or detached from the 45 wristband of the shirt sleeve.

It will be obvious that modifications may be made in the details of my cuff without changing the scope of the invention, and

that the cuff may be made with or without a lining and of one ply or more of material.

Although I have shown the preferred construction of my cuff using eight buttonholes in each cuff I am aware that the cuff may be made with a lesser or greater number of buttonholes, which will proportionately lessen or increase the number of usable or wearing portions of the cuff.

Having thus fully described the invention, what I claim as new and desire to secure by Letters Patent is:

1. As a new article of manufacture, a tubular detachable cuff for shirt sleeves, having four button holes equally spaced along each lateral margin thereof.

2. As a new article of manufacture an endless detachable cuff of two or more plies of material, the sides of said endless cuff being open, so that the cuff may be turned inside out for the purpose of doubling the 70 number of clean portions or wearing edges of the cuff, and at least four button holes equally spaced around the circumference of each of the open sides of said cuff, so that the cuff may be folded transversely half-way between any two button holes to cause 75 said two button holes to register with each other and also with the two buttonholes on the opposite side of the cuff, said buttonholes being adapted to register with the buttonholes in the wristband of a shirt sleeve, whereby the sides of the cuff may be drawn together and attached to the wristband by means of a button or link.

3. As a new article of manufacture, a 80 detachable soft cuff for shirts made in the form of a tube and provided adjacent each of its lateral margins with four buttonholes, the buttonholes at both margins being similarly positioned, so that when the cuff is 90 folded, the buttonholes at one margin may be brought into registration with the corresponding buttonholes at the other margins.

In testimony whereof I have signed the foregoing specification.

JUDSON C. EUBANK.
